HEAT TRANSFER DEVICE

Warren S. Blauvelt, Troy, N. Y., assignor to
 Blauvelt Associates, Inc., Troy, N. Y., a corpora-
 tion of New York

Application May 3, 1939, Serial No. 271,485

4 Claims. (Cl. 138—38)

My invention relates, in general, to an improvement in the transfer of heat through the walls of a tube through which a first fluid flows and which is surrounded by a second fluid, heat being transferred through the walls of the tube either from the fluid within the tube to that without the tube or the reverse.

The principal object of my invention is an improvement in the transfer of heat through the walls of a tube from one fluid to another by the use of a suitable baffle element disposed within said tube through the walls of which heat is to be thus transferred.

A more specific object of my invention is an improvement in the transfer of heat from the heated gases passing through a fire tube of a boiler to the water surrounding the same although it is to be understood that my invention is not limited to this particular use.

Other objects of my invention will appear in the specification and the novel features thereof will be more particularly pointed out in the claims.

My invention will best be understood by reference to the accompanying drawing in which I have illustrated a preferred embodiment thereof and in which

Fig. 1 is a longitudinal sectional view through a fire tube of a boiler and showing a multiple baffle element embodying my invention, in front elevation, disposed in said tube and providing a series of constricted openings between the baffle and the tube which, upwardly, are of successively smaller cross sectional area, and

Fig. 2 is a similar view through a baffle element in which the enlargements are all of the same size and the constrictions between said enlargements and the associated tube would all have substantially the same areas.

Like reference characters indicate like parts throughout the drawing.

Referring to the drawing, and first to Fig. 1, 10 is a fire tube of a boiler, the boiler being represented by upper and lower tube sheets 11 and 12 provided with respective openings 13 and 14 in which the respective ends of the fire tube are welded or otherwise secured and sealed. A first fluid which, in the case of a boiler, is heated gas, flows upwardly through the tube and the tube is surrounded by a second fluid which, in the illustrated embodiment of my invention, is water.

In accordance with my invention, a baffle element, indicated generally at 15, is disposed within the fire tube in spaced relation thereto and preferably concentric therewith. Such baffle ele-

ment is preferably formed of cast iron or other good heat conducting material and which at the same time has the characteristic of resisting corrosion and erosion by the fluid flowing through the tube.

The volume of gas is, of course, directly related to its absolute temperature, and its density, under a given pressure, varies inversely with its absolute temperature. The pressure loss in passing through a constricted opening varies as the square of its velocity and directly as its density, and where the temperature of the gas to be cooled varies over a wide range such as 2000°, in passing through a tube in which the multiple baffle is inserted, the areas of the constricted openings through which the gas successively passes are successively reduced as the temperature and volume thereof are reduced, or are successively enlarged if the passing gas is to be heated over a wide range and thereby greatly expanded.

The baffle element 15 embodying my invention is preferably disposed concentrically within the tube 10 and in order to maintain the same in such concentric position, the baffle is preferably cast with a plurality of outwardly extending arms or pins 18. In the embodiment of my invention illustrated, four such pins are extended outwardly near the lower portion of the baffle and four other pins 181 extend outwardly near the upper end of the baffle, the baffle conveniently being supported by a hook 19 and eye 191.

In the embodiment of my invention illustrated in Fig. 1, the successive enlargements 16 progressively increase in diameter to form with the tube 10 constricted flow areas 20 which are successively reduced in the direction of flow of the gas in the tube, such areas being considerably less than that of a tube section at that point and producing an increase in the velocity of the gas as compared with the velocity that would obtain if the baffle element were not present and other conditions remained the same. The edge of a given enlargement is defined by a line in a plane generally perpendicular to the longitudinal axis of the tube and to the general direction of the flow of gases through the tube and presents a sharp edge. Such constriction greatly reduces the friction due to the flow of gas through each restricted flow area resulting from the enlargement of the baffle in that plane as compared with any restriction which continues for any appreciable distance. The eddy currents which are promptly set up in the enlarged gas flow area immediately following the above restriction in-

crease the turbulence of flow and correspondingly increase the rate of heat transfer from the gases to the tube.

The effectiveness of heat transfer is still further increased by the passage of radiant heat either from the surface of the baffle element to the surface of the tube and thence to the liquid surrounding it, or by radiation from the wall of the tube to the surface of the baffle element. As the outer surface of the baffle element 15 is not in contact with the fluid surrounding the tube but is in contact with the fluid passing through said tube, the surface of said baffle tends to assume the temperature of the fluid with which it is in contact, modified, however, by radiation from its surface to the surface of the tube if the fluid passing through the tube is at a higher temperature than the fluid surrounding the tube or by radiation to the surface of the baffle element from the surface of the tube if the fluid surrounding the tube is hotter than the fluid passing through said tube.

Where heat is to be transferred from a fluid surrounding tube 10 to a gas passing therethrough, the gases to which heat is to be transferred would be caused to flow downwardly through the tube 10, the constricted flow areas between the enlargements of the baffle and the tube 10 being successively increased in the direction of the flow of gases.

The effectiveness of heat transfer of gases is further increased by the turbulence produced in the gases by the presence of the successive constrictions and enlargements of the baffle. It is well known that when heated gases flow through a plain tube there is a film of gas molecules which may be considered substantially in contact with the inner surface of the tube and moving at a low velocity compared with the mean velocity of the gas passing through the tube, thus retarding, or interfering with, the heat transfer from the body of the gas to the tube. Whatever breaks up or reduces the thickness of such viscous film, or reduces the time of contact of the gas molecules in said film with the tube walls, tends to accelerate the heat transfer. The successive baffles, 16, which greatly constrict the flow area at their edges cause the advancing streams of gases which, flowing through the tube, are to be brought toward temperature equilibrium with the fluid surrounding the tube, to flow past said baffle edges at a suddenly increased velocity and to approach said constricted flow areas at a relatively abrupt angle with the wall of the tube, thereby greatly reducing the thickness of the viscous film of gas adjacent to the wall of the tube and increasing the turbulence of flow of said gases when approaching, when passing, and when receding from each of the said restricted flow areas between the outer edge of each baffle and the tube wall, thus facilitating the desired heat transfer. By making the portion 21 of the baffle element which defines the angle of recession in the flow of gas from each enlargement 16 more nearly parallel to the axis of the tube than portion 22 which defines the angle of approach, the pressure differential required to cause the gas to flow at any given velocity through a tube in which the baffle element is placed appears to be less than is required with other relationships between the angles of approach to and recession from the restricted flow areas at the outer edges of the successive baffles, with the wall of the tube.

The baffle element is preferably made hollow as indicated by dotted lines 23. The upper end

of the baffle may be provided with a plug 24 to which a hook 19 and eye 191 are attached and when removed, forms an opening through which the sand core may be removed.

While my invention is particularly adapted to facilitate heat transfer in a boiler, it is to be understood that it is equally well adapted to transfer heat in a recuperator, a condenser, or any other form of heat transfer device in which either a gas or a liquid flows through a tube and in which the baffle element embodying my invention is placed. Furthermore, it may be used in the same way to transfer heat from a fluid, either liquid or gas which surrounds a tube to a fluid, either gas or a liquid which passes through the tube.

In the embodiment of my invention illustrated in Fig. 1 where there is a wide variation in the temperature of the gases in the tube, and where heat is to be transferred from said gases to a fluid surrounding the tube, the width of the zones located between the enlargements of the baffle are successively reduced in the direction of the flow of the gas as the temperature and consequently the volume thereof are reduced, the widest zone, 25, being located nearest the bottom of the baffle element where the gases are hottest, and the narrowest zone, 25a, being nearest the top of the baffle element where the gases are coolest. On the other hand, where heat is to be transferred from a fluid surrounding the tube to a gas within the tube, the width of the zones of the baffle should progressively increase in the direction of flow of gases if such gases are to be heated through a wide temperature range. Except for fillets 26 which are preferably formed at the bottoms of the contractions, each zone is formed of two frustums, the larger base of each frustum being united to the larger base of the next following frustum and the smaller base of each frustum being joined to the smaller base of the next succeeding section. For example, the zone 25 comprises two frustums 251 and 252, the smaller base of the frustum 251 being joined to the smaller base of the following frustum 252 and the larger base of the frustum 252 being joined to the larger base of the following frustum 253.

Where the range of temperature of a gas passing through a tube in which the multiple baffle element embodying my invention is to be inserted is comparatively small, say 100° or thereabouts, there is little advantage in varying the cross sectional area of the constricted passages and in Fig. 2 I have illustrated an embodiment of my invention which is suitable for use in such a situation and where the passages between the enlarged portions of the baffle and the surrounding tube are all of the same, or substantially the same, area. The baffle is, however, formed with alternate enlargements and constrictions in the same general way as that shown in Fig. 1 and will break up the viscous film which would normally be located adjacent the inner surface of the tube.

I have found in practice that the baffle element embodying my invention very greatly increases the heat transfer of gas passing through a fire tube to the water surrounding the same and experimental data indicates that with a suitable baffle embodying my invention installed in a boiler flue two feet long, the heat recovery in the flue as evidenced by the reduction of the temperature of the gas in passing therethrough exceeds the similar heat recovery in an ordinary boiler tube sixteen feet long.

While I have described my invention in its pre-

ferred embodiment it is to be understood that the words which I have used are words of description rather than of limitation and that changes within the purview of the appended claims may be made without departing from the true scope and spirit of my invention in its broader aspects.

5 What I claim is:

1. In a heat transfer device, a tube, a single multiple baffle element disposed within and spaced from said tube to form a passage for the flow of a first fluid and formed with a continuous outer surface, said baffle element having alternately circumferential crests and valleys for imparting turbulence to the first fluid in its flow 10 15 through the said passage between said baffle element and said tube, said tube being surrounded by an enclosure adapted to contain a second fluid.

2. In a heat transfer device, a tube, a single multiple baffle element disposed within and substantially concentric with said tube and spaced therefrom and forming therewith a passage through which a fluid may flow, the outer wall of said passage being substantially straight and uninterrupted in the direction of flow of said fluid, 25 alternate portions of said baffle element having the general form of frustums of cones, the larger base of a given frustum being also the larger base of a following frustum, and the smaller base of a given frustum being united to the smaller base 30 of the next following frustum, the angle of inclination of a given conical surface with respect to the axis of the frustum being greater with respect to the direction of flow of gases approaching the constrictions of the passage through the

tube than the similar angle of inclination of the frustum leaving such construction.

3. In a heat transfer device, a tube, a single multiple baffle element disposed in said tube and formed of frustums of cones, the larger base of a given frustum being also the larger base of the following frustum and the smaller base of a given frustum being united with the smaller base of the following frustum, said baffle being spaced from said tube to form a passage for the flow 10 15 20 of a first fluid, two given frustums forming a zone and the width of the zones varying in the direction of the flow of said fluid, said tube being surrounded by an enclosure adapted to contain a second fluid.

4. In a heat transfer device, a tube the inner surface of which is substantially straight in the direction of its longitudinal axis, a single multiple baffle element disposed concentrically within and spaced from said tube to form a passage 25 for the flow of a first fluid and formed with a continuous outer surface, said baffle element having alternately radially enlarged and radially reduced peripheral portions, the flow area between a given enlargement of said baffle and such tube being decreased at each such enlargement and increased following each such enlargement in the direction of flow of said fluid, and having the flow areas both at their enlargements and at their following reductions successively decreased 30 and the distance between such reductions in flow area also successively decreased, said tube being surrounded by an enclosure adapted to contain a second fluid.
